HYDROTHERAPY FOOT TUB

Samuel L. McNair and Henry J. Talge, Overland Park,
Kans., assignors to Dazey Products Company

Filed July 23, 1973, Ser. No. 381,677

Term of patent 14 years

Int. Cl. D24—04
U.S. Cl. D83—1 C

Fig. 4.

Fig. 5.

FIG. 1 is a top plan view of a hydrotherapy foot tub showing our new design;

FIG. 2 is a side elevational view thereof;

FIG. 3 is a sectional view taken on line 3—3 of FIG. 1 in the direction of the arrows;

FIG. 4 is an end elevational view from thereof, taken from the left hand end of FIG. 1; and

FIG. 5 is an end elevational view thereof, taken from the right hand end of FIG. 1.

We claim:

The ornamental design for a hydrotherapy foot tub, as shown and described.
